GRAIN DOOR

Melville Lindsay, Crestwynd, Saskatchewan,
CanadaApplication September 29, 1931, Serial No.
565,821, and in Canada September 30, 1930

3 Claims. (Cl. 20—28)

This invention relates to improvements in grain doors and an object of the invention is to provide a simplified structure of this character which will readily retain grain within a car and may be easily operated to release the grain when it is desired to unload it.

A further object of the invention is to provide a simplified type of structure which may be stored within the car within a minimum of space without constituting an obstruction.

A still further object of the invention is to provide a structure which may be manufactured at a reduced cost.

With these and other objects in view, the invention consists essentially of a grain door formed with the main section which is swingably attached to the car door frame, said section hinged carrying two minor sections which as a unit constitute the whole grain door when in closed position, with means for securing and releasing the door, as more fully described in the present specification and illustrated in the accompanying drawings which form part of the same.

25 In the drawings:—

Figure 1 is a fragmentary elevation of the interior of a railway car showing the door mounted in closed position.

Figure 2 is a section taken on the line 2—2 of Figure 1.

Figure 3 is a similar view to Figure 1 showing the door in stored position.

Figure 4 is a fragmentary sectional detail of the hinged connection of the main portion of the door, and

Figure 5 is a sectional detail of an alternative form of locking means for the door.

Referring more particularly to the drawings, A indicates the car as a whole and B indicates the grain door. The door B is preferably made up of three parts, viz, the main door section 10, which is formed with a hinge unit 11 adapted to be mounted on the hinge mounting rod 12 which is positioned at one side of the door frame within the interior of the car.

The hinge rod 12 is mounted in a recess formed between the upper and lower parts of the door frame 13 and 14, more particularly illustrated in Figure 1.

50 The smaller or auxiliary door sections 15 and 16 are hingedly connected across the upper and lower edges respectively of the main door 10, as clearly indicated in Figure 3, and as a whole the door is adapted to fit in a recess 17 in the interior wall of the car, as illustrated in Figure 1.

Locking members 18 are provided at one side of the recess 17, so as to co-operate with corresponding members 19 in the door structure, so that the structure may be rigidly fastened within the recess 17 when it is not in use. 60

On each side of the door frame spaced apart projecting plates 20 are secured which seal the joint between the door frame and the door structure, and thus immediately prevent the escape of any grain through these joints. At 65 the same time these plates will constitute a support for the hinged auxiliary sections of the door. On one side of the door frame a lip is formed between the plates to receive the outer edge of the main section. 70

As illustrated in Figures 1 and 3, these plates are secured on the inside of the door frame, and will not in any way interfere with the opening of the hinged sections, particularly the lower hinged section, when it is desired to discharge 75 the grain.

Apart from this, these plates constitute a securing means for the door when it is placed in closed position, for the reason that to close the door it is necessary to swing auxiliary sections 80 15 and 16 outwardly upon the main door section 10, so that the outer edge of the main section 10 of the door may contact with the door frame between the plates 20. The sections 15 and 16 will then be swung up and down into normal 85 position and come to rest in contact with the door frame behind the plates 20 the inner end edges of the auxiliary sections contacting with the plates. Thus it is impossible to return the door structure to inoperative position without 90 folding the auxiliary sections 15 and 16 back upon the main section 10.

Accordingly it will be seen that apart from the use of locking members or the like for preventing the auxiliary door sections from moving outwardly on their hinges, no securing means is required to retain the whole unit in its closed position. 95

In order to retain the lower section 16 in closed position and to provide means for readily releasing it, locking bars 21 are slidably positioned in the floor of the car outside of the door section 16 and these members are pivotally carried upon an operating lever 22 which is pivoted as at 23 below the car floor. 100

A guide 24 is positioned intermediate the ends of the lever and a locking guide 25 is positioned towards the free end of the lever on the under side of the car so that, as illustrated in Figure 1, the lever may be swung into engagement with 110

the locking guide, and a seal or other fastening device may be secured to keep it in place. When the lever is swung into normal closed position, as illustrated in Figure 1, it will be noted that the locking bars 21 protrude through the floor and embrace the outside of the lower section 16, so that it is then prevented from moving in either direction.

Another form of locking arrangement is shown in Figure 5, which is very similar to that as disclosed in the other figures, including the operating lever 22 and locking bars 21 but both locking bars are not operated directly from the lever 22. In this form a second lever 26 is pivoted to the combination locking member and guide 27 which at its opposite end is swingably connected as at 28 with the operating lever 22. The lever 26 is connected to one of the locking bars 21 as at 29 similar to the connection between the lever 22 and the other locking bar 21 so that upon movement of the operating lever one of the locking bars 21 is directly brought into engagement, or withdrawn from engagement, with the outer edge of the door while the other locking bar 21 is indirectly similarly moved with the lever 26, the operating of both locking bars being simultaneous. The operating lever in this form may be sealed similarly as in the other form disclosed.

To discharge the grain it is a simple matter to release the seal and operate the lever mechanism to withdraw the locking bars 21 from contact with the lower section 16, so that the grain immediately forces the section 16 outwardly and discharges. Of course, it will be understood that any suitable form of locking means could be employed to retain this section in place.

As a whole, it will be seen that I have provided a very simple type of grain door structure, which may be used to considerable advantage in the handling of the grain, and when not in use will take up very little space within the car, and will not in any way interfere with the use of the car for other purposes.

Various modifications may be made in this invention without departing from the spirit thereof or the scope of the claims, and therefore

the exact forms shown are to be taken as illustrative only and not in a limiting sense, and it is desired that only such limitations shall be placed thereon as are disclosed in the prior art or are set forth in the accompanying claims.

What I claim as my invention is:—

1. A grain door comprising a unit attachable to a car door frame including a main section swingably mounted on one side of the door frame, a lip formed in the opposite side of the door frame to receive the outer end edge of said main section, a pair of auxiliary sections hingedly attached to the upper and lower edges of said main section and swingable with said main section, a pair of spaced apart projecting plate retaining members secured to each side of the door frame adapted to abut the inner end edges of the auxiliary sections to seal the joints between said sections and the door frame, and means in connection with the door frame for locking and releasing one of said auxiliary sections.

2. A grain car door comprising a unit attachable to a car door frame including a main section provided with a hinged unit on one side adapted to be attached to a hinged mounting rod secured in a recess between the upper and lower parts of the door frame, a pair of auxiliary sections hingedly attached to the upper and lower edges of said main section and swingable with said main section, means for retaining the unit in inoperative position, means for retaining the unit in operative position, and means in connection with the door frame for locking and releasing one of said auxiliary sections, including a pair of locking bars adapted to slide through the base of the door frame to abut one side of said auxiliary section, and an actuating member connected with said locking bars adapted to operate said bars into or out of engagement with said auxiliary section, and means for securing said actuating member in locked position.

3. A device as claimed in claim 1, in which a bar is secured between a pair of said plates on one side of the door frame, the main section being rotatably mounted upon said bar and swinging therewith.

MELVILLE LINDSAY.
